[57] **CLAIM**

The ornamental design for sound bar for a percussion instrument, as shown.

DESCRIPTION

FIG. 1 is a top plan view of a sound bar for a percussion instrument showing my new design;

FIG. 2 is a front view thereof;

FIG. 3 is a bottom plan view thereof;

FIG. 4 is a left-side view thereof;

FIG. 5 is a right-side view thereof;

FIG. 6 is a rear view thereof;

FIG. 7 is a sectional view thereof taken along line 7—7 of FIG. 2;

FIG. 8 is a sectional view thereof taken along line 8—8 of FIG. 4;

FIG. 9 is a sectional view thereof taken along line 9—9 of FIG. 5; and,

FIG. 10 is a sectional view thereof taken along line 10—10 of FIG. 2.

FIG. 1

FIG. 2

FIG. 3

FIG. 4

FIG. 5

FIG. 6

FIG. 7

FIG. 8

FIG. 9

FIG. 10
